ROTARY TYPE CAN OPENER

Robert E. McLean, Fort Francis E. Warren, Wyo.

Application April 14, 1942, Serial No. 438,947

20 Claims. (Cl. 30—9)

The present invention relates generally to the class of implements or tools designed for opening sealed receptacles of metal such as tin cans and the like, and the present application is based upon and sets forth certain improvements over the structure disclosed in my copending application relating to rotary type can openers, Serial No. 409,419, filed September 3, 1941.

The devices herein set forth, as well as those in my prior application above referred to, employ a crank means which upon rotation effects the shifting of a portion of the device for the purpose of bringing about the penetration of the head of the receptacle which is to be opened, by a cutting knife, and the turning of the receptacle with respect to such knife upon continuation of the rotation of the crank. The crank carries a means which cooperates with a portion of a fixed part of the implement for bringing about the initial movement between the receptacle head and the knife, and in my prior application the handle carried means is in the form of a spring actuated reciprocal element which has intermittent movement for a short distance longitudinally of the handle or crank.

A particular feature of the present application constituting an improvement over my prior application resides in the provision of a novel and improved form of the handle or crank carried means, which, in cooperation with other parts of the implement, brings about the relative movement between the can head and the cutting knife, whereby a more compact construction of the implement may be produced and quieter operation of the implement is obtained.

Another object of the present invention is to provide a rotary type can opener having a swinging or pivoted crank handle carried latch or escapement for coaction with an eccentric wheel actuating lever and releasing cam pawl.

Still another object of the invention is to provide a rotary type can opener in which the cam pawl is designed to cause the crank handle carried latch or escapement to return to an initial position without the creation of unpleasant noise.

Still another object of the invention is to provide, in a rotary type can opener, a novel head construction carrying the cutting knife, which permits of a degree of flexibility between the knife and the can flange engaging driving wheel whereby variations in thickness in the metal of the cans may be readily handled by the implement and relative movement between the knife and wheel is permitted to allow for the passage

5 of seams or other unusual thickened portions.

Another object of the invention is to provide in a rotary type can opener a novel construction providing a holding means engageable with the top edge of a can while the head is being cut therefrom, to maintain the can against rocking or other movement which might interfere with the correct cutting out of the head.

10 The several forms or embodiments of the improved pivoted latch or escapement, together with the other improved features of the cutter as herein disclosed, will be best understood from a consideration of the following detailed description taken in connection with the accompanying drawings, it being understood, however, that the invention is not to be considered as limited by the specific illustration or description of such embodiments but that the illustration and description constitute preferred forms of the improved 15 embodiments.

In the drawings:

Figure 1 is a view in side elevation of one embodiment of the improved rotary can opener, showing the operating crank handle swung clockwise past its hanging position and the driving wheel actuated cam in wheel raising position.

Figure 2 is a view in top plan of the implement as shown in Figure 1.

Figure 3 is a vertical section taken on the line 20 3—3 of Figure 1.

Figure 4 is a view in elevation of the upper portion of the implement upon the side opposite from that shown in Figure 1, a part of the head being broken away.

25 Figure 5 is a view in elevation of a portion of the side of the crank opposite from that shown in Figure 1, and showing the pivoted latch or escapement in side elevation.

Figure 6 is a view in perspective of the lower 30 part of the can top edge engaging and steadyng bracket.

Figure 7 is a side elevational view of another embodiment of the rotary can opener, corresponding to Figure 1.

Figure 8 is a view in front elevation of the embodiment shown in Figure 7, with a portion of the operating crank removed.

Figure 9 is a central vertical longitudinal section through the embodiment shown in Figure 7.

Figure 10 is a view in top plan of a modification of the pivoted latch or escapement which is carried by the operating handle.

Figure 11 is a view in side elevation of the escapement shown in Figure 10, looking at the

same from the side of the crank upon which it is located.

Figure 12 is a view in side elevation of the escapement shown in Figure 10, viewed from the side opposite from that shown in Figure 11.

Figure 13 is a view in top plan of the escapement per se as shown in Figure 10, and viewed in flat plan as contrasted with Figure 10 in which the escapement is partially in perspective.

Figure 14 is a view in side elevation of a modified form of latch engaging pawl.

Figure 15 is a view in edge elevation of the pawl shown in Figure 14.

Figure 16 is a view in side elevation of a further embodiment of pawl and escapement mechanism.

Figure 17 is a sectional view taken on the line 17—17 of Figure 16.

Figure 18 is a view in front elevation of the lower portion of the pawl and escapement mechanism shown in Figure 16.

Figure 19 is a sectional view taken substantially on the line 19—19 of Figure 16.

Figure 20 is a view in side elevation of still another embodiment of pawl and escapement mechanism.

Figure 21 is a view in front elevation of the mechanism shown in Figure 20.

Figure 22 is a sectional view taken substantially on the line 22—22 of Figure 20.

Referring now more particularly to the drawings wherein like numerals indicate corresponding parts in these several views, reference will first be had to the embodiments particularly set forth in Figures 1 to 6 inclusive.

In the embodiment of the invention illustrated in the figures particularly referred to it will be seen that the main body portion of the implement is in the form of a flat relatively long plate body indicated generally by the reference character 1^c and having a laterally offset upper end portion 2^a which merges with a horizontal laterally directed part 3^a which in turn adjoins a downwardly extending portion or face piece 4^c which is in spaced parallel relation with the portion 2^a. These portions 2^a, 3^a and 4^c form the head of the device and provide between the spaced portions 2^a and 4^c a receiver for a cutting blade 5^c, the lower edge portion of which is sharpened, as indicated at 5^d, and is obliquely angled, as shown in Figure 4.

The portion 2^a has the two apertures 94 formed therethrough and coaxial with these apertures are formed in the portion 4^c the threaded apertures 95. The cutting blade 5^c is provided with suitable apertures for alignment with the apertures 94 and 95 and there is disposed between the blade and the portion 2^a the apertured plate 96 which, as shown in Figure 6, has the transverse bar 97 across its lower end which terminates in the forwardly directed and slightly convergent fingers 98. These fingers, as shown in Figure 4, are disposed above the cutting edge 5^d of the blade and also slightly above the shoulder 113' which is formed, as shown in Figure 3, by offsetting the portion 2^a from the main body portion or plate 1^c.

Below the shoulder 113' the body plate 1^c has the central longitudinally extending elongated recess 8^d formed therein. Extending through this recess 8^d is a sleeve 9^b which, intermediate its ends, is enlarged to form the integral collar 10^b which is of a diameter equal to the width of the recess 8^d in which it has vertical movement.

Extending through the sleeve 9^b is a bearing 75

sleeve 12^d which is secured against rotation in the sleeve 9^b and extending through and rotatably supported in the bearing sleeve 12^d is a driving wheel shaft 13^d. This shaft supports upon 5 one end the crank handle 14^d by the provision of a reduced longitudinal extension 15^d which engages in an aperture of the crank handle and which has its end swaged over, as indicated at 16^d, to maintain the crank handle in position.

Upon the opposite end of the shaft 13^d from the handle is a driving wheel 17^d which has its periphery knurled or toothed for operative connection with the bead or flange of a metallic can, a portion of which is shown in dotted outline 15 in Figure 3 and indicated by the character 18^d. This knurled or toothed wheel lies in the plane of the plate 96 and to one side of the plane of the knife 5^c, as shown, so that it may force the can upwardly through engagement with the edge flange thereof and cause the pointed edge of the knife to penetrate the top of the can.

Upon the end of the sleeve 9^b nearest the wheel 17^d there is secured an eccentric wheel 19^c which, as shown in Figure 4, has two joining right angularly related tangential straight edge portions 20^b and 21^b, one of which, namely the portion 20^b, comes to rest near the shoulder 113' when the eccentric wheel is rotated in a direction to raise the driving wheel 17^d, thus limiting the rotary motion of the eccentric wheel in the said one direction. The periphery of the eccentric wheel is at all times in contact with the shoulder 113' as well as with an underlying supporting unit, hereinafter described, against which the straight portion 21^b comes to rest upon reverse rotation of the eccentric wheel to lower the driving wheel 17^d.

The numeral 22^d indicates a lever arm which has an upper inset portion 23^d through which the 40 sleeves 9^b and 12^d pass, as shown in Figure 3, this portion being securely fastened to the sleeve 9^b whereby rotation may be imparted thereto and transmitted to the eccentric wheel 19^c upon turning of the lever. As shown in Figure 3, the main 45 lower portion of the lever is substantially spaced from the adjacent face of the plate 1^c to permit the disposal against this face of a pawl 24^d which is pivotally suspended from the stud 102, as shown in Figure 3.

The lower edge of the pawl 24^d is curved eccentrically to the pivotal center for the pawl and forms a cam 26^d which extends at its lower end below the lowermost part of the lever 22^d, as shown in Figure 1, when this lever is hanging 55 or suspended in the manner illustrated.

Clockwise rotation of the pawl 24^d is limited by the stud 28^d which forms a stop which the pawl engages at one side.

The side of the lever arm 22^d remote from the 60 movement limiting stud 28^d for the pawl is cut away at its lower end to form the obliquely directed shoulder 27^d, with which cooperates an escapement hereinafter described.

Rotary movement is imparted to the crank handle 14^d by the pivoted knob 29^d which is mounted upon the free end of the handle.

Upon the side of the plate body 1^c against which the eccentric wheel 19^c is located, there is secured a spring supporting plate 39^b from the rear edge of which there curves upwardly and forwardly the spring arm 40^b, against the top edge of which the eccentric wheel 19^c bears, as shown in Figure 4.

From the foregoing it will be readily apparent that upon turning the lever arm 22^d in one di-

rection the eccentric wheel, bearing upon the spring arm 40^b, and against the shoulder 113^b, will raise the collar 10^b in the opening 8^d to lift the driving wheel toward the cutting blade and when rotated in the opposite direction the driving wheel will be lowered away from the blade, thus making it possible to effect the easy penetration of the point of the blade through the top of the can after the latter is placed in position with the driving wheel engaging against the under edge of the can flange.

A suitable supporting bracket arm 41^d is provided for the implement, one end of which arm is secured to the implement, as shown in Figure 3, while the other end may be attached in any suitable manner through the medium of a T 41^e with a suitable wall attached keeper device. Such device is here shown as being in the form of a plate having forwardly turned opposite edge portions a' which are reverted to provide the flanges b' which are in spaced relation with the body proper of the plate.

Means for preventing the accidental displacement of the bracket arm 41^d from the wall attached keeper is here shown as comprising a keeper slot c' formed in one flange b' and a substantially U-shaped spring d' secured to the side of the bracket arm 41^d and having one leg riveted or otherwise secured to the bracket arm, as shown at e', while the other leg f' is resiliently engaged in the recess c', as illustrated in Figure 2.

The actuation of the lever arm 22^d is accomplished in the manner above described for effecting the raising and lowering of the can driving wheel as well as the can, by means of a pivoted latch or escapement 103 which is mounted upon the crank handle 14^d. This escapement 103 comprises a small flat plate 104 which is disposed in edge opposed relation with the inner side of the crank handle or, in other words, the side thereof nearest the lever arm 22^d. This plate has an edge shoulder 105 which engages against that edge of the crank which would be the trailing edge when the crank is given clockwise rotation, and terminates in an angularly disposed lip 106 which is designed to engage the oblique shoulder 27^d of the lever. The angle of the lip 106 is such as to engage flat against the shoulder 27^d when these two parts are brought into operative relation.

The opposite edge of the plate 104 is formed to provide a bearing sleeve 107 and this receives a pin 108 which is secured at one end in the side of the crank handle.

Encircling the pivot pin 108 between the end of the sleeve 107 and the handle is a spring 109 which has one end secured, as indicated at 110, to a stud 111 carried by the handle while the other end 112 bears against the under side of the plate 104 and normally urges it to swing in a direction to bring the shoulder 105 against the adjacent edge of the handle.

It will be apparent from the foregoing that when the driving wheel 17^d is in lowered position the collar 10^b will be in the lower part of the opening or recess 8^d and, consequently, the shouleder lower end of the lever arm 22^d will be in a radius below the camming edge 26^d of the pawl.

With the parts in the position shown in Figure 1, when the handle or crank 14^d is given clockwise rotation the edge of the lip 106 will ride along the camming edge of the pawl 24^d and will be carried by this edge below the lower end of the lever arm 22^d. Thus, when the driving wheel

10 is in the raised position shown the crank handle can be continually turned to effect the cutting out of the head of the can. After this has been accomplished, the operator by giving a counter-clockwise movement to the crank handle will bring the back of the lip 106 against the edge of the lever arm 22^d opposite from the shoulder 27^d which will effect the reverse rotation of the lever until the straight edge portion 21^b of the eccentric wheel has been brought around against the top edge of the spring 40^b and this will result in lowering the driving wheel 17^d with respect to the knife and, if a can is in the machine the can will be released from engagement between the driving wheel and the knife. The lever arm 22^d will thus be left in a position where, upon subsequent movement of the crank in a clockwise direction, the top face of the lip 106 will be brought into engagement with the edge face of the shoulder 27^d, and as the lever arm is forced downwardly and forwardly the driving wheel will be raised in the manner previously stated and the edge of the lip 106 of the escapement will ride down along the edge 26^d of the pawl and thereby be disengaged from the shoulder 27^d as the latter rises with the driving wheel.

In Figures 7 to 9 inclusive another embodiment of the invention is illustrated wherein the body plate of the implement is indicated by the reference character 1^d and this plate, at its upper end, is offset to form the shoulder 113 and then continues upwardly and obliquely to form the head consisting of the forward portion 114, the rearwardly extending short portion 115, and the downwardly extending portion 116 which is in spaced parallel relation with the portion 114. The portion 116 has an aperture 117 therethrough and is slightly bowed away from the portion 114, as indicated at 118 in Figure 8, while the portion 114 of the head has a similar aperture 119 except that it is flattened at the bottom (not shown) to prevent rotation of bushing 75^a which is coaxial with the aperture 117.

Extending through the aperture 117 and into the aperture 119 is a bearing sleeve 75^a which is transversely flattened at its forward end, as indicated at 120, to engage a correspondingly flattened portion of the opening 119 whereby the sleeve is held against rotation but, as shown, it may have a slight longitudinal movement.

Extending through the bearing sleeve 75^a is a shaft 77^a having the head 81^a upon the rear end which bears against the collar 82^a which forms an integral part of the rear end of the bearing sleeve and rests against the bowed portion 118. The opposite or forward end of this shaft has rotatably mounted thereon the knurled idler wheel 79^a which is spaced from the forward or adjacent end of the bearing sleeve 75^a but bears against the portion 114. Upon the end of the shaft 77^a there is secured the cutting wheel or circular knife 78^a which maintains the idler wheel in position.

The longitudinally extending opening in the body plate is indicated in this embodiment of the invention by the reference character 8^c through which extends the sleeve 9^c which has the collar 10^c which slides in the opening and the bearing sleeve is here indicated by the character 12^c, through which extends the driving wheel shaft 13^c and upon the rear end of which is secured the crank handle 14^c. As indicated at 16^c the same means is here shown for securing the handle upon the shaft but any other suitable

means may be employed, as will be readily apparent, and upon the opposite end of the shaft from the handle and located directly beneath the idler wheel 79^a is the knurled or toothed driving wheel 17^c.

The eccentric wheel is here indicated by the character 19^d and is mounted upon the sleeve 9^c and bears at its top against the shoulder 113. It will be readily understood that this bearing wheel may be of the same design as that shown in Figure 4 and at its lower edge it bears against the spring arm 40^c which forms an integral part of the plate 39^c which is secured to the body of the implement.

A portion of a supporting bracket for the implement is also shown secured to the body and to the plate 39^c and is indicated by the character 41^c.

The lever arm 22^c is also of the same general design as that shown in Figure 1 and is secured at its upper end to the sleeve 9^c as illustrated, the lower end portion being offset and in spaced relation with the body 1^d. The oblique shoulder at the lower end of this lever arm and at the rear or trailing edge is indicated by the character 27^c, but it will be noted that this lever arm tapers off to a materially less width at its lower end than does the arm 22^d so as to more efficiently cooperate with the adjacent pawl 24^c. This pawl 24^c is pivotally suspended upon the lug or pivot member 102^a and is limited in its forward swinging movement by the stop member 28^c which is carried upon the body plate.

The lower edge of the pawl 24^c has a slightly different bottom edge configuration from the pawl 24^d in that in addition to having the long curved or arcuate camming edge 26^c which is eccentric to the pivot 102^a and which passes or extends slightly below the free end of the lever arm 22^c, it has the forwardly and upwardly curving camming edge portion 121 with which it merges at the lowermost point 122, which low point is in a plane directly beneath the free end of the lever arm when the latter is hanging straight down as shown. This camming edge arrangement of the pawl 24^c facilitates the smooth and quiet return of the pivoted latch or escapement unit 103^a, which is carried upon the crank handle 14^c, to its stationary position. The parts of this latch or escapement are the same as shown in Figure 1 and the same reference numerals are employed for corresponding parts with the addition of the subscript *a*.

In the operation of the implement shown in Figures 7 to 9 it will be readily understood that when the eccentric wheel 19^d is turned in a direction to lower the driving wheel 17^c the lever arm 22^c will be swung rearwardly or to the right of the position in which it is shown in Figure 7 and, consequently, when the receptacle is placed in position with the top flange located above and resting upon the driving wheel 17^c and the crank handle is turned clockwise by grasping the knob 29^c, the escapement 103^a will be brought around until the lip 106^a engages the oblique shoulder 27^c of the lever arm and continued turning of the handle will rotate the arm and the eccentric wheel and cause the driving wheel to raise the can, turning the can and at the same time forcing its head against the sharp edge of the rotary knife 78^a. As the lower end of the lever arm swings down the edge of the lip 106^a will ride along the camming edge 26^c of the pawl until it is forced by this edge to swing relatively to the crank handle to a position where it will pass off 75

of the shoulder 27^c and it will then ride around the low point 122 and ride up on the ascending or rising camming edge 121 so as to be allowed to slowly come back to its position where the shoulder 105^a rests against the edge of the crank handle. Thus the escapement is allowed to return to its normal or inactive position without noise.

It will also be apparent from the foregoing that due to the novel construction of the upper or head portion of the plate body of the implement, when a thickened portion of a can wall, such as a seam or the like, passes between the face of the driving wheel 17^c and the adjacent side of the cutting wheel the portion 116 will yield or flex so as to permit the shaft 77^a and the sleeve 75^a to shift slightly. In this way the seam or thickened portion will pass smoothly between the driving wheel and cutter without damaging the implement and without stopping or interfering with the proper operation of the implement in cutting out the head of the can.

Figures 11 to 13 illustrate another form of escapement which might be used in the place of the escapements 103 and 103^a, in association with a cam pawl of any desired shape or contour which may be mounted in a fixed position upon the body plate of the implement instead of being pivoted as are the cam pawls 24^d and 24^e. The cam surface of such a fixed cam pawl would preferably be of approximately the same design as the pivoted cam pawl 24^c referred to and such stationary cam pawl might be used with any of the several embodiments of the invention. In illustration of this modified escapement construction a portion of the supporting crank handle only is shown, the same being indicated by the character 14^f and a portion of the actuating knob, shown in Figure 10, being indicated by the character 29^f.

This escapement comprises the plate 104^b which is arranged in edge opposed relation with the inner side of the crank handle 14^f and is cut to form the shoulder 105^b, Figures 10 and 13, which engages against the edge of the crank handle which becomes the trailing edge when the handle is given clockwise rotation. A portion of this plate adjacent the shoulder 105^b is turned up to provide the lip 106^b corresponding with the lip 106 of the structure shown in Figure 1 and designed to engage the oblique shoulder 27^d or 27^e at the free end of the lever arm. The opposite end of the plate from the lip 106^b is formed to provide the bearing sleeve 107^b which receives the supporting pin 108^b which is secured at one end to the crank handle.

At opposite sides of the lip 106^b the plate is turned to form the aligned sleeves 123 through which is extended the pin 124. This pin is carried entirely by the plate 104^b and in the portion lying beneath the lip 106^b it is slightly reduced in diameter and has wound thereabout the coil spring 130, one end of which, not shown, is fixed to the pin, while the other end indicated by the numeral 131, is engaged over the top of the plate.

Upon the opposite side of the plate from the shoulder 105^b the plate is cut out, see Figures 11 and 13, to receive a pawl 127 which is mounted upon and secured to the reduced terminal portion 125, Figure 11, of the adjacent end of the pin 124. This pawl is shaped to provide the point 129 at the inner end of which is formed the lug 128, which lug is normally urged to bear against the under side of the plate at the inner end portion 126 of the recess in which the pawl

is located. The pawl is constantly urged to this position by the spring 130 which couples the pin 124 with the escapement plate.

Upon the pivot post 108^b there is mounted between the plate 104^b and the adjacent face of the crank arm, the spring 109^b, one end of which is secured to the crank arm by the stud 111^b while the other end bears against the under side of the escapement plate and constantly urges it to oscillate in a direction to bring the shoulder 105^b into position against the edge of the crank arm.

As previously stated, the pivoted escapement or latch mechanism 103^b is designed for use in association with a cam pawl which is fixed upon the body plate of the implement instead of being pivoted like the pawls 24^d and 24^e. Therefore, when the crank handle 14^c is turned clockwise, assuming that the lever arm of the implement has been swung counter-clockwise to a position where the eccentric wheel has turned sufficiently to lower the driving wheel to its lowermost position, the lip 106^b will engage against the oblique shoulder of the lever arm, such as the shoulder 27^c, for example, and will swing the lever arm with it in a clockwise direction until the driving wheel has raised to its uppermost position and moved the can so as to force the cutter through the head of the can. As the lever arm is moving into this position the point 129 of the escapement carried pawl 127 will ride along against the lower edge of the cam pawl and will cause the escapement plate to swing on its pivot 108^b until the lip 106^b is freed from engagement with the lever arm. Continuous rotation of the crank handle can then take place to completely cut out the head of the can.

In order to restore the lever arm to the position where the driving wheel is lowered to inoperative position and the can is released, a reverse or counter-clockwise rotation will be given to the crank handle so as to bring the back of the lip 106^b against the forward or advancing edge of the lever arm until the latter has been swung to the desired position. During this movement the back edge of the point 129 will strike the fixed cam pawl and the escapement will be permitted to pass the fixed pawl by the oscillation of the pawl 127 against the tension of the coil spring 130. The crank handle may then be swung back or allowed to return by gravity to hanging position and the implement is ready for reuse.

Figures 14 and 15 illustrate a type of fixed or non-swinging cam pawl which might be used in association with the type of escapement just described and illustrated in Figures 10 to 13 inclusive. As shown, this fixed pawl is in the form of a roller or wheel 24^c which is mounted upon the body plate of the implement here indicated by the reference character 1^c. This roller may be secured against rotation if desired but in either case it will present the desired curved camming edge 26^c for engagement by the opposite edge faces of the point 129 of the escapement pawl 127. The lower end of the lever arm associated with this cam pawl 24^c is indicated by the character 22^c.

Figures 16 to 22 inclusive set forth two further embodiments of the invention which have certain features of construction in common.

In Figures 16 to 19 the body plate is indicated by the character 1^d and has the usual longitudinally extending opening 8^d with the eccentric wheel engaging shoulder 113^a at its upper end and

the portions 114^a, 115^a, and 116^a making up the head of the device. Through the apertures 117^a and 119^a there extends the sleeve bearing 75^b which, as in the structure shown in Figures 7 to 9, supports a shaft 77^b having upon its rear end the head 81^b and upon its forward end the cutting wheel 78^b. Between this wheel and the head portion 114^a is the can flange engaging idler wheel or roller 79^b. As in the case of the previously described structure the bearing sleeve has the flattened portion 120^a which corresponds with the portion of the opening in which the end of the bearing engages, to maintain the bearing sleeve against turning.

15 The opening 8^d has the bearing sleeve 9^d therethrough which carries the collar 10^d which slides in the opening and this bearing sleeve supports the shaft bearing 12^d through which extends the shaft 13^d, one end of which carries the crank lever 14^d while the other end carries the driving wheel 17^d. 16^d indicates the head of the shaft which secures the lever thereon.

As in the other cases, the body of the implement is secured to a spring arm plate 39^d from 25 which extends the spring arm 40^d and to the bracket plate 41^d. Between the spring arm 40^d and the shoulder 113^a is the eccentric wheel 19^d which is secured, as in the other embodiments, to the forward end of the bearing sleeve 9^d.

30 The character 22^d designates the lever arm which is secured at one end to and supported upon the bearing sleeve 9^d. This lever arm adjacent its free end carries upon its outer side, or that side remote from the body plate 1^d, the small roller 133 which is mounted, in slightly spaced relation with the lever arm, upon the supporting pivot stud 133^d.

Between the lever arm 22^d and the plate body 1^d is mounted upon the pivot stud 102^b which is 40 secured to the plate, the swinging or pivoted pawl 24^d which has an arcuate lower edge 26^d which is eccentric to the pivot. The arcuate edge 26^d is bordered upon the face of the pawl opposite from the plate 1^d, by the outstanding flange 134 which, at the rear side of the pawl, is 45 slightly rounded upwardly, as indicated at 135, Figure 16, while at the forward edge of the pawl the flange terminates in the short straight upwardly extending portion 136, Figures 17 and 18.

50 The plate 1^d supports, at the forward edge of the pawl 24^d, the stop or abutment stud 28^d which limits the forward swinging movement of the pawl.

The character 103^c designates the pivoted escapement carried by the crank handle 14^c. This escapement comprises a pivot element 137 which is carried by the crank and to which is pivotally connected one end of a short link bar 138, disposed upon the inner side of the handle. At its 55 other end the link bar 138 has attached thereto one end of a trip finger 139 which is of circular cross-section and which is of sufficient length to extend inwardly across the camming edge 26^c and flange 134 of the pawl 24^c, as is shown in Figures 17 and 18.

Upon its top edge the link bar 138 carries the laterally projecting stop lug 140 which projects across the adjacent edge of the handle 14^c. This lug limits the swinging movement of the link in 60 one direction.

Below the pivot 137 the crank carries a stud 141 to which is secured one end of a short leaf spring 142, the other end of which bears against the lower edge of the link 138 and constantly urges it to swing upwardly, thereby maintaining

the stop 140 in contact with the trailing edge of the crank handle.

In this embodiment of the invention, when the lever 22^g is in the raised position shown in broken lines in Figure 16, in which position the eccentric wheel 19^e will be lowered so as to lower the driving wheel 17^e to a position to permit the insertion of a can flange between the wheel and the cutter 78^b, if the crank 14^g is turned clockwise the trip finger 139 will engage the roller 133 inwardly of the pivotal center thereof and thus firm contact will be maintained between the finger and the roller to cause the lever 22^g to be pulled around for the purpose of turning the eccentric wheel and raising the driving wheel 17^e. As the clockwise movement of the crank handle continues the trip finger 139 will ride, at its inner end, against the higher part of the camming edge and flange of the pawl 24^g and be caused by this edge to move downwardly, thus swinging the free end of the link 138 downwardly also against the tension of the spring 142. When the lever 22^g has swung down to the limit of its movement the center of the trip finger 139 will have been moved by the camming edge of the pawl below the pivotal center of the roller 133, as shown in Figure 16. It will thus be seen that continued pull of the trip finger 139 against the roller, below the pivotal center of the latter, will cause the finger to ride down and under the roller, thus permitting the continued clockwise rotation of the crank handle. The tensioned spring 142 will return the link 138 to the position where the stop 140 engages the edge of the crank. After the head of the can has been cut the can may be released by turning the crank counter-clockwise so as to bring the trip finger 139 against the opposite side of the roller 133 and since the finger will be above the pivotal center of the roller it will maintain firm contact therewith until the lever 22^g is returned to the broken line position shown in Figure 16. It will, of course, be understood that in this return movement the pawl 24^g can swing in a counterclockwise direction to permit the finger to pass. This swinging action also takes place, as will be understood, in connection with the pawls 24^a and 24^e to permit the counter-clockwise turning of the handles associated therewith.

In the embodiment set forth in Figures 20 to 22 inclusive it will be understood that, although the full implement is not illustrated, the construction of the upper part thereof is the same as in Figure 17 and also that the body plate 1^g supports the bearing sleeve 12^g and the eccentric wheel 19^e and driving wheel 17^e for vertical movement, the eccentric wheel turning against the shoulder 113^b at the upper end of the body plate, while the lower edge of the eccentric wheel bears against the spring arm 40^e which forms an integral part of the plate 39^e which is secured to the body plate, and which in turn has secured thereagainst the supporting bracket 41^g.

In this construction, the lever 22^h which is operatively coupled with the eccentric wheel 19^e in the same manner as illustrated in Figure 17, has an outwardly rounded or arcuate end edge 143 which is eccentric to the turning axis of the lever and in the back or trailing edge there is formed a shallow recess 144 while the forward or advancing edge has formed therein the deeper recess 145. The lower ends of these recesses merge with the arcuate edge 143, as shown in dotted or broken outline in Figure 20.

The pawl 24^h which is pivotally mounted upon the body plate 1^g, through the medium of the pivot stud 102^g, has the eccentric lower camming edge 26^h, Figure 20, the lower end of which extends slightly below that end of the curved edge 143 of the lever arm which is highest when the lever arm is in the vertical depending position shown in full lines in Figure 20.

In this embodiment the escapement comprises the pivot 137^a which is supported upon or secured to the crank handle 14^h and the link bar 138^a which is pivotally attached to the pivot 137^a and which carries, at the end remote from the pivot, the trip finger 139^a which, like the finger 139, extends inwardly toward the body plate. This trip finger is designed to engage and ride on the camming edge 26^h of the pawl 24^h.

The link bar 138^a carries upon its top edge the stop lug 140^a, Figures 20 and 22, which extends laterally across the edge of the handle 14^h and by engagement with this edge limits the upward swinging movement of the link bar. Below the pivot 137^a is a stud 141^a to which is attached one end of a leaf spring 142^a, the other end of which spring engages the adjacent edge of the link bar and constantly urges it to swing upwardly, whereby the stop 140^a is maintained in contact with the crank.

The trip finger 139^a has rotatably supported thereon the lever arm contacting roller 147. This roller is in the plane of the recessed portion of the lever arm 22^h and is adapted to engage in the recesses 144 and 145 and to roll across the arcuate lower end edge 143.

When the implement is set to receive a can, the head of which is to be removed, the lever arm 22^h will be disposed in the raised position in which it is shown in broken lines in Figure 20, in which position it will be understood that the driving roller 17^h will be lowered from the cutter, not shown. The pawl 24^h will, of course, be in hanging position and in engagement at its forward edge with the stop stud 28^g.

If clockwise rotation is now given the crank handle, the trip finger carried roller 147 will be brought around in position to engage in the shallow recess 144 of the lever arm and continued turning of the crank handle will effect the downward swinging of the lever arm to the final position in which it is shown in full lines in Figure 20. However, before this full line position is reached the inner end of the trip finger 139^a will contact the high side or end of the camming edge 26^h of the pawl 24^h and the finger, together with the link 138^a, will begin to swing down against the tension of the spring 142^a, causing the roller 147 to roll out of the recess 144 onto the high end of the end edge 143 of the lever, as shown in Figure 20. The downward swinging of the link bar will continue until the roller 147 has been lowered to the position where it may roll across the end 143 of the lever, thereby permitting continued clockwise turning of the handle. Restoration of the lever 22^h to the dotted or broken line position shown in Figure 20, for the release of the can after the head has been cut out, is effected by imparting counter-clockwise movement to the crank handle, whereupon the roller 147 will engage in the recess 145 of the lever and force the lever to swing back to the desired position. The pawl 24^h will swing out of the way during this return movement of the lever to raised position, to permit the trip finger 139^a to pass, the pawl

subsequently returning by gravity to its position of rest against the stop lug 28^g.

From the foregoing it will be readily apparent that in the several embodiments of the invention herein disclosed and described, the pivoted latch or escapement mechanism is, in all cases, pivotally supported upon the crank handle and by engagement with the pawl carried by the plate body of the implement is caused to oscillate, when the crank is turned in a clockwise direction for the purpose of securing the can in position and simultaneously effecting the penetration of the head by the knife and the cutting out of the head, to effect a disengagement of the escapement from the eccentric wheel turning lever after the latter has been turned to the desired position. Upon counter-clockwise movement of the crank handle, the pivoted latch or escapement mechanism being returned to normal position with respect to the handle, effects the restoration of the lever to the position in which the eccentric wheel is turned to lower the can driving wheel or effect separation of the driving wheel from the cutter or knife.

In the first part of this specification it is stated that the present application is based upon and presents certain improvements over my prior application, and in this connection it is pointed out that any one of the various forms of escapement herein illustrated and described can be adapted to each of the embodiments of the can opener set forth in the prior application.

I claim:

1. A can opener, comprising a body member, a cutter carried thereby, a rotatable can driving wheel carried by the body, the cutter and wheel having relative movement to effect penetration of a can top by the cutter, a thrust means for effecting such relative movement, a crank for turning the wheel, a lever for actuating the thrust means, and mechanism pivotally mounted on and carried by the crank adapted for releasable coupling with the lever upon turning of the crank for effecting actuation of the thrust means and relative movement of the wheel and cutter.

2. A can opener, comprising a body member, a can top cutter carried thereby, means carried by the body for effecting rotational movement of a can when the same has had its top penetrated by the cutter, said means being movable relatively to the cutter for effecting penetration of the top by the cutter, means including a turnable arm for shifting said first means relatively to the cutter, means for effecting actuation of the first means to impart rotary motion to the can, and a mechanism pivotally supported upon said last mentioned means adapted for releasable connection with said arm upon actuation of the means for imparting rotary motion to the can for effecting relative movement between the cutter and the can rotating means.

3. A can opener, comprising a body member, a can top cutter carried thereby, a rotatable can driving wheel carried by the body for cooperative action with the cutter, the cutter and wheel having relative movement to effect penetration of a can top by the cutter, means for rotating the wheel, a rotatable means adjacent the first means for effecting the said relative movement between the cutter and wheel, and including a lever, a latch mechanism pivotally supported upon the wheel turning means and adapted to engage said lever, and mechanism for effecting oscillation of the latch and its release from con-

nexion with the lever when a predetermined relative movement has been effected between the cutter and the wheel.

4. An implement as set forth in claim 3, in which the last mentioned mechanism comprises a camming element functioning to oscillate the latching mechanism to a position in which it may pass across the free end of the lever arm.

5. A can opener, comprising a body member, a cutter carried thereby, a rotatable can driving wheel carried by the body, the cutter and wheel having relative movement to effect penetration of a can top by the cutter, a thrust means for effecting said relative movement, a crank for turning the wheel, a lever arm for actuating the thrust means, a pivot carried by the crank, a body carried by the pivot for oscillation on an axis paralleling the axis of rotation of the crank, means carried by the pivoted body for effecting an operative coupling between the pivoted body and said lever arm, whereby the lever arm will be turned in a direction to actuate the thrust means upon turning the crank in one direction, and means for releasing the operative connection between the said means of the pivoted body and the lever arm when a predetermined relative movement between the crank and driving wheel is effected.

6. A can opener as set forth in claim 5, including means resiliently urging oscillation of the pivoted body in a direction to position the arm engaging means thereof for connection with the arm upon turning the crank in the said one direction, and means for limiting the oscillatory movement of the pivoted body under the action of said resilient means.

7. A can opener, comprising a supporting body, a can top penetrating cutter carried thereby, a rotatable can driving wheel carried by the supporting body, the cutter and wheel having relative movement to facilitate penetration of a can top by the cutter, a thrust means for effecting such relative movement, crank means for turning the wheel, a lever arm operatively coupled with the thrust means for actuating the latter, an escapement carried by the crank and comprising a plate member pivotally supported upon the side of the crank nearest said lever arm, means carried by the plate and extending transversely thereof for engaging a side of the lever arm upon rotation of the crank in one direction to effect turning of the arm and actuation of the thrust means, and means for effecting oscillation of the plate after a predetermined extent of rotary movement of the arm to disengage the plate carried means from the arm.

8. A can opener as set forth in claim 7, in which said plate oscillating means is constructed and arranged to permit passing of the plate when the latter is moved in the opposite direction with said crank, the pivoted plate when moved in the said opposite direction engaging and imparting reverse motion to the lever arm for reversely actuating the thrust means.

9. A can opener, comprising a body member, a can top penetrating cutter carried thereby, a rotatable can driving wheel carried by the body, said wheel being supported for movement relative to the cutter to effect penetration of a can top by the cutter, a rotatable thrust element for effecting such relative movement, a crank for rotating the wheel, a lever connected with and adapted to turn the thrust element, an escapement mechanism comprising a plate disposed in edge opposed relation with the side of the crank

nearest the lever, pivotal means supporting the plate on the lever for oscillation on an axis paralleling the turning axis of the plate, said plate having an edge flange arranged for connection with a side of the lever when the crank is turned clockwise, resilient means normally urging oscillation of the plate in a direction to engage the flange against an edge of the crank, and a camming means carried by the body for engagement by the plate flange to effect oscillation of the plate to an extent to free the flange from the lever arm when a predetermined relative movement between the wheel and cutter has been effected.

10. A can opener as set forth in claim 9 in which said camming means has two oppositely directed portions joined by an intermediate portion, one of said portions functioning to oscillate the plate to a point of disconnection from the lever arm, the intermediate portion carrying the flange of the plate across the end of the lever arm, and the other portion functioning to prevent the too rapid reverse oscillation of the plate.

11. A can opener, comprising a body member, a can top penetrating cutter carried thereby, a rotatable can driving wheel carried by the body, the wheel being supported to have movement relative to the cutter to effect penetration by the cutter of a can top, a thrust means connected with the wheel for effecting such relative movement, a crank for turning the wheel, a rotatable lever for actuating the thrust means, a pawl pivotally suspended upon the body between the same and the lever, and having an eccentric camming edge, and a lever arm engaging and actuating escapement unit comprising a member having one end pivotally connected with the crank for oscillation on an axis paralleling the axis of turning of the crank, spring means engaging the escapement member and urging oscillation of the same toward the pivoted end of the crank, a stop shoulder carried by the last mentioned means for limiting said oscillatory motion, and an element carried by the escapement means and extending transversely of the crank from the crank toward the body member and adapted for connection with the lever arm to turn the same for effecting the stated relative movement between the cutter and driving wheel when the crank is turned in one direction, said element riding over the pawl cam to effect the oscillation by the cam of the escapement member against the action of said spring means to an extent to effect the disengagement of the escapement element from the end of the lever arm.

12. A can opener, comprising a body member, a cutter carried thereby, a rotatable can driving wheel carried by the body, the wheel being supported for movement relative to the cutter for facilitating the penetration of a can top by the cutter, a thrust means operatively coupled with the driving wheel for effecting when actuated the stated relative movement between the wheel and cutter, a crank for turning the wheel, a lever arm operatively coupled with the thrust means and turnable to effect actuation of the latter, means carried by the body between the same and the lever arm providing a fixed cam, and a lever arm actuating escapement comprising an elongated body having an end pivotally attached to that side of the crank nearest the lever arm to oscillate on an axis paralleling the rotary axis of the crank, spring means connected with said element and urging oscillation of the same in a direction to swing the other end toward the piv-

oted end of the crank, a stop shoulder carried by the element and engaging the crank to limit the oscillation of the element, a flange at the other end of the element arranged for operative connection with the lever arm upon clockwise rotation of the crank to effect movement of the driving wheel relative to the cutter, a pivoted pawl carried upon said element and arranged for movement over and in contact with said cam means on rotation of the crank in the said one direction, the pivoted pawl being held against pivotal movement when in the stated contact with the cam means but yielding for oscillation when reversely moved against said cam means, and spring means resisting the said yielding action of the pivoted pawl.

13. A can opener, comprising a body member, a cutter carried thereby, a rotatable can driving wheel carried by the body, said wheel being supported for movement relative to the cutter to facilitate penetration of a can top by the cutter, a thrust means operatively coupled with the driving wheel for effecting movement of the same relative to the cutter, a crank arm connected with the wheel for turning the latter, a lever arm operatively coupled with the thrust means and turnable to effect actuation of the latter, a short link bar pivotally attached at one end to the crank arm and projecting beyond the trailing edge of the latter, a trip finger secured at one end to the trailing end of the link bar and extending transversely with respect to the crank arm toward the body member, spring means normally urging oscillation of the link bar in a direction to dispose the trip finger to engage across the free end of the lever arm upon either clockwise or counter-clockwise turning of the crank arm, and means providing an arcuate camming surface between the lever arm and the body member for engagement by the trip finger to effect the swinging of the link bar against said resilient means to an extent to facilitate the passage of the finger across the end of the lever arm when the latter is moved a predetermined distance by the finger in a clockwise direction.

14. A can opener of the character set forth in claim 13, with a rotatable element carried upon the free end of the lever arm for engagement by and to facilitate the movement of the finger across the end of the lever arm.

15. A can opener as set forth in claim 13, with a roller element carried by the finger for contacting the lever arm and to facilitate movement of the finger across the free end of the lever arm.

16. A can opener, comprising an elongated plate adapted to be mounted vertically, the plate having an off-set upper part providing a shoulder, said upper part consisting of two spaced parallel portions, a knife mounted between said portions and having a lower downwardly directed cutting edge, a plate secured with the knife between said portions and having lateral can edge engaging arms in a plane slightly above said edge, a can flange engaging driving wheel below and in the plane of said plate, a rotary thrust means engaging said shoulder and carrying said wheel and adapted to move the wheel relative to the knife, a lever coupled with said thrust means for actuating the latter, a crank for turning said wheel, and means carried by the crank adapted to releasably couple with the lever upon turning the crank in one direction to effect actuation of the thrust means and movement of the wheel relative to the knife.

17. A can opener as set forth in claim 16, in

which one of said portions forms an integral continuation of the plate body and the other portion is free at one end but joined at its other end to the first portion to have resilient movement relative to the first portion, and said knife and plate are secured only to the said other portion for movement therewith relative to the first portion.

18. A can opener, comprising an elongated plate adapted to be mounted vertically, said plate having an integral offset obliquely directed an upper portion terminating at its upper end in a lateral intermediate portion and a second oblique portion connected at one end with the intermediate portion and having its other end free, a shaft extending through and supported by said oblique portions, a circular knife secured to the end of the shaft adjacent the first oblique portion, an idler roller on the shaft between the knife and adjacent portion, the other end of the shaft being held against axial movement through the other oblique portion, a rotary can flange engaging wheel, a thrust means supported by the body and bearing against said shoulder and supporting said wheel to effect movement of the

wheel relative to the knife, a crank for said wheel, a lever coupled with the thrust means for effecting actuation of the latter, and a latch mechanism carried by the crank designed to releasably couple with the lever upon turning of the crank in one direction to actuate the lever and thrust means to move the wheel relative to the knife.

19. A can opener as set forth in claim 18, including a bearing sleeve through which said shaft passes, the sleeve having a head upon the end remote from the knife and bearing against the side of the second portion remote from the knife, the other end of the sleeve terminating in the first oblique portion and coupled therewith against turning but having free longitudinal movement therein.

20. A can opener as set forth in claim 18, with means carried by the plate for effecting the automatic release of said latch mechanism from the lever when a predetermined actuation of said thrust means has been effected.

ROBERT E. MCLEAN.
